END CONNECTER FOR TUBES

Application filed November 8, 1929. Serial No. 405,688.

My invention relates to end connectors for tubes and has a particular reference to connectors and attachments for tubes forming batteries for heating liquids.

According to the usual practice of building such batteries, the ends of each pair of tubes are connected together by a casting or separate forging, there being as many such connectors as there are pairs of tube ends. Such connectors, however, have certain disadvantages, for instance:

1. Their design does not permit to use more than two tubes in parallel or four tubes for each connector. For certain applications, however, it is desirable to use a larger number of tubes in parallel in order to increase the effective heating surface, to reduce the time for heating under the same pressure, and to reduce the thickness of the tube walls at high pressures.

2. The ordinary construction of such return bends is such that it does not permit the arrangement of tubes with small clearances between them. The clearances, however, should be made as small as it is practical, in order to increase the velocities of the hot gases thereby increasing the efficiency of the heat exchange.

3. The total weight of the battery is considerably increased when separate connectors are used for each pair of tubes.

4. The ordinary construction of batteries used for cracking petroleum oils is not suitable for capacities in excess of about 3000 barrels in 24 hours, as the sizes of individual pipes become too large for the pressures and temperatures involved and it becomes impossible to increase the speed of the operation.

In order to provide return bends and connectors free from the above defects, also to render them suitable for applications requiring high pressures and high temperatures, for instance, in heating and distilling (or cracking) petroleum oils or similar hydrocarbons, I make such connectors in the form of blocks adapted to receive the ends of a plurality of tubes connected in any desired number of parallel groups and sections.

I make these blocks from steel forgings and provide them with milled chambers for con-

nnecting the ends of tubes or parallel groups of tubes in any suitable number. I also provide special end plugs consisting of two concentric screws, the inner screws being used for clamping the sealing gaskets between tapering surfaces.

My invention is more fully described in the accompanying specification and drawing in which—

Fig. 1 is an elevation of my battery partly in section showing the tube connectors, Fig. 2 is a plan view of same partly in section, and Fig. 3 is a detailed view of a connecting block in section.

My connector consists of a block 1 made preferably of a solid steel forging. It has a plurality of transverse apertures 2. These apertures on one side of the block are provided with circular grooves 4 into which the ends of tubes 5 are expanded. On the other side of the block the apertures are counterbored to a larger diameter forming a tapering shoulder 6 inside. The counterbored or enlarged portion is provided with threads 7 for screw blocks 8. Connecting chambers or channels 9 are milled inside of the block 1 between the ends of the pipes 5 and under the tapered seats 6. These channels form communications between the adjacent tubes or groups of tubes. For this purpose any desired number of tubes can be connected in one group (in parallel) placing them across the block, or at an angle as shown on the drawing. Sealing tapered plugs 10 are placed between the tapered shoulders 6 and the screw plugs 8. The lower ends of these sealing blocks 10 are made to conform to the shape of the seats 6. The screw plugs 8 have recesses 11 for the heads 12 of the blocks 10. These heads are undercut by grooves 13 so as to facilitate their removal from the block by a suitable tool. Sealing gaskets 14 are placed between the seats 6 and blocks 10. These gaskets can be made of a soft metal such as copper or aluminum (or soft iron) in the form of continuous rings. Bolts 27 press the blocks 10 against the seats 6 thereby compressing and squeezing the wire rings 14.

The block 1 is preferably made of a sufficient length so as to extend through the full

length of the battery of tubes. A number of blocks can be placed side by side, as shown in Fig. 2, in order to increase the total heating surface and to more fully utilize the heat of gases. The end connector for the blocks 1 5 consists of a short block 15 made substantially as the main block 1 with transverse apertures 16 and inner counterbore 17. In order to connect it with the main block 1 the latter in the last hole 2 has recesses 4 for a short nipple 18 instead of the threads 7. The block 15 has also end holes 19 for cleaning the chambers formed by counterbore 17. This hole is closed with a screw plug 20 pressing against a tapered plug 21 resting on a tapered seat 22.

15 A similar connector is used for intake and exhaust pipes 23. The connector consists of a block 24 similar to the block 15 except that the two holes 25 and 26 are located at right angles to each other. This arrangement is 20 made in order to facilitate the mounting of these pipes in the furnace.

Important advantages of my tube connectors are that they can be made of a solid steel 25 forging thereby eliminating the possibility of leakage through the metal which often happens at high pressures and temperatures when steel castings are used, also when the parts are made by a welding process. The use 30 of a single block for the whole row of the tubes makes possible a very close spacing of the tubes thereby making the construction more compact, the blocks lighter for a given capacity, increasing also the velocity of gases 35 between the tubes and the coefficient of heat exchange. My improved construction of the plugs permits their easy replacement and repacking, eliminating leakage and rendering them suitable for very high temperatures and 40 pressures.

I claim as my invention:

1. In a tube end connector, the combination 45 with a block of an elongated shape provided with a plurality of transverse apertures, of plugs closing said apertures on one side of said block, said apertures on the other side of said block being adapted to receive the ends of tubes, said apertures inside of said 50 block being eccentrically counterbored, said counterbores of each consecutive pair of said 55 apertures merging into each other so as to form a communicating passage inside of said block between said adjacent apertures.

2. A tube end connector, consisting of a 55 block with a plurality of transverse apertures, said apertures on one side of said block being adapted to receive threaded plugs, and on the other side of said block being adapted to receive the ends of tubes, said block being 60 eccentrically counterbored inside of said apertures, said counterbores of each consecutive pair of said apertures being arranged to merge into each other thereby forming a passage inside of said block between said adjacent apertures.

3. A tube end connector, consisting of a block with a plurality of transverse apertures arranged in consecutive groups, said apertures on one side of said block being adapted to receive the ends of tubes and being concentrically counterbored to allow for expansion of the ends of said tubes, said apertures on the other side of said block being adapted to receive sealing plugs, said block being eccentrically counterbored inside through said apertures, said eccentric counterbores of each pair of consecutive groups of said apertures being arranged to merge into each other thereby forming passages between said groups inside of said block.

4. In a tube end connector, the combination with a block provided with a plurality of transverse apertures, said apertures on one side of said block being adapted to receive the ends of tubes, and on the other side of said block being provided with tapered seats, of tapered plugs adapted to fit said tapered seats, said apertures above said tapered block being threaded, screw plugs fitted into said threads without touching said tapered plugs, 90 central raised portions on said tapered plugs, said portions being undercut at their bases and provided with cup-shaped depressions on top, and screws fitted into said screw plugs and provided with convex ends adapted to fit 95 said cup-shaped depressions, said screw plugs being provided with recesses at the bottom forming clearances around said raised portion of said tapered plugs, said blocks being provided with internal channels forming 100 communications between succeeding groups of said apertures.

In testimony whereof I affix my signature.
MATVEY A. CAPELIUSCHNICOFF.
